GRILL FOR A VENTILATING FAN

Cicero Hunt Lewis II, Arcadia, Calif., assignor to Trade-Wind Motorfans, Inc., Los Angeles, Calif., a corporation of California

Application April 12, 1954, Serial No. 29,958

Term of patent 14 years

(Cl. D26—7)

Fig. 1.

Fig. 2.

To all whom it may concern:

Be it known that I, Cicero Hunt Lewis II, a citizen of the United States, residing in the city of Arcadia, county of Los Angeles, and State of California, have invented a new, original, and ornamental Design for a Grill for a Ventilating Fan, of which the following is a specification, reference being had to the accompanying drawing, forming a part thereof.

Fig. 1 is a perspective view of a grill for a ventilating fan embodying my new design, being a view taken from the front and one side thereof.

Fig. 2 is a perspective view of the instant design being a view taken from the back and other side thereof.

I claim:

The ornamental design for a grill for a ventilating fan, as shown.
